UNITED STATES PATENT OFFICE.

ALBERT A. JARDIN, OF CONGRESS PARK, ILLINOIS, ASSIGNOR OF ONE-HALF TO
JOHN McANDREW, OF BERWYN, ILLINOIS.

RAILROAD-SWITCH.

1,295,755.

Specification of Letters Patent.

Patented Feb. 25, 1919.

Application filed November 26, 1917. Serial No. 204,046.

To all whom it may concern:

Be it known that I, ALBERT A. JARDIN, a citizen of the United States, and a resident of Congress Park, in the county of Cook 5 and State of Illinois, have invented certain new and useful Improvements in Railroad-Switches, of which the following is a full, clear, and exact description.

The invention relates to railroad switches. 10 It is now common practice to provide two movable switch points at the junction of a main track and a side track, one switch point for each rail or side of the track. These switch points are subjected to great 15 wear so that they must be frequently replaced, thus entailing a considerable cost of maintenance.

One object of the present invention is to provide an improved construction in which 20 a single switch point at one side of the track is sufficient to control the movement of the trains onto either of the tracks, the one rail on each side of the track being formed of a substantially continuous rail section.

25 Another object is to provide a railroad switch of improved construction.

The invention consists in the several novel features hereinafter set forth and more particularly defined by claims at the conclusion 30 hereof.

In the drawings: Figure 1 is a plan of the track and switch embodying the invention. Fig. 2 is a section taken on line 2—2 of Fig. 1. Fig. 3 is a section taken on line 35 3—3 of Fig. 1. Fig. 4 is a perspective of the locking wedge for securing the rail sections and filler blocks together.

The invention is shown as applied to a construction in which a main line track is 40 connected to a switch-track 6. One side of the main line track is formed of a continuous straight rail 6 and the other side is formed by a rail 7, which at the switch, extends continuously and laterally to form 45 the other side of the main track and the outer side of the switch track, as at 8, so that when the train is traveling on the main line, the rail at one side will be continuous and when the train is passing from the main 50 track to the switch track, one rail of the track traversed by the train will be continuous. From the switch point on, there is a rail 9 forming the second side of the main track and a rail 10 forming the inner 55 side of the switch track.

A switch point 11 suitably pivoted or connected to the end of the rail 10 is adapted, when in position shown in Fig. 1, to direct the car wheels on the main line and to act as a guard which holds the wheels 60 from moving inwardly off the track 6. When the switch point 11 is shifted into position shown by dotted lines, it will deflect the wheels to cause the train to move onto the switch track. In this manner, a single 65 switch point serves conjointly to deflect the train and as a guard rail for holding the train on the main line track. At the side opposite the switch point, rail 9 is tapered, as at 13, and a guard rail 14 is provided at 70 the inside of the rails 7 and 9. The ends of the guard rail 14 are curved to guide the wheel flanges onto the track. The end of rail 10 and rail 6 are held in spaced relation by a block 15 and these rails are secured together with the block 15 therebetween by a clamping bracket 16 which extends under the rails, as at 17, and engages the inner side of rail 10, as at 18, and is provided with a flange 19. A wedge 20 adapted to be 80 driven between the rail section 6 and flange 19 is adapted to secure these rails and the block 15 together. The wedge 20 is provided with a series of holes 21 which are adapted to receive a locking pin 22 which may be 85 dropped through any of the holes into position to engage the edge of the bracket 16 to prevent its release. Rails 8, 9 and 14 are properly spaced apart by a block 23 which is slotted to receive the end 13 of 90 rail 9 and is adapted to engage the inner side of rail 7 and the outer side of the guard rail 14. These rails and the block 23 are secured together by two clamps 24 and 25 similar in construction to the clamp 16 95 and wedges 20 similar in construction to the wedge used in clamp 16.

The deflection in rail 7 to curve one side of the switch track is disposed to commence at the point where the switch point 11 commences to deflect the car wheels when the switch is in position shown in dotted lines in Fig. 1 or in position to direct the train onto the switch track. The gap between the end of rail 9 and the curved portion of 100 rail 7 is so narrow that the tread of the car wheel will bridge it so that the wheel will pass onto rail 9 before it leaves rail 7 when the train is running on the main track. When the train is being directed onto the 110

side track, the switch point 11 will force the flanges of the car wheels laterally to direct the car onto the side track. It will be understood that any suitable means, such as a rod 30 may be employed to operate the switch point.

The invention exemplifies a switch in which a single switch point to control the movement of the train from the main track 10 onto a side track and in which the track opposite the switch is formed of rail sections, one of which is continuous; also one which is adapted for use with a comparatively short switch point; also one in which 15 the joint between the sections opposite the switch is formed by rail sections and blocks secured together by clamps.

The invention is not to be understood as restricted to the details set forth, since these 20 may be modified within the scope of the ap-

pended claims, without departing from the spirit and scope of the invention.

Having thus described the invention, what I claim as new and desire to secure by Letters Patent, is:

In a railroad track construction, the combination of a continuous straight rail at one side of the track, a curved rail for a side track at the same side, a switch point movable into position to direct a car-wheel onto either of said rails, a continuous rail at the second side of the track forming a part of the main track and curved to form the outer side of the switch-track, a rail section having a tapered end forming the second side of the main track and separate means for securing said tapered end and the continuous rail for the second side of the track in fixed relation.

ALBERT A. JARDIN.
